JIB CRANES

Howard L. Bushman, Wayne, Ill.

Application June 22, 1953, Serial No. 363,203

2 Claims. (Cl. 212—28)

This invention relates to jib cranes, and particularly to the way in which the rotatable jib is mounted on the supporting standard or column of such a crane.

Jib cranes have, of course, been constructed in many different ways, but one of the most common arrangements has included a column made from a relatively large cylindrical pipe, with the jib rotatably supported on the upper end of the column by means including laterally acting anti-friction rollers which roll upon the outer surface of the cylindrical column. In such prior structures, it has been found that the attainment of a proper rolling relationship of the anti-friction rollers upon the surfaces of the cylindrical column has been extremely difficult to attain, and this has been due, at least in part, to the fact that the columns are not in every instance produced with true cylindrical outer surfaces, and it has also been due to the fact that inaccuracies of original manufacture or inaccuracies due to progressive wear of the parts have caused the anti-friction bearings to engage the column along lines at edge contact rather than with a true and complete rolling engagement. It is, therefore, an important object of the present invention to simplify and improve the construction of jib cranes so that a proper application of the load-imposed forces between the column and the jib may be attained in every instance, and a related object is to attain this result in a simple and inexpensive manner.

Other and further objects of the present invention will be apparent from the following description and claims and are illustrated in the accompanying drawings which, by way of illustration, show a preferred embodiment of the present invention and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims.

In the drawings:

Fig. 1 is an elevational view of a jib crane embodying the features of the invention;

Fig. 2 is a fragmentary plan view of the crane;

Fig. 3 is an enlarged cross sectional view taken along the line 3—3 of Fig. 1;

Fig. 4 is a fragmental view taken in vertical section along the line 4—4 of Fig. 3; and

Fig. 5 is a side elevational view of one of the bearing carriers.

For purposes of disclosure, the invention is herein illustrated as embodied in a jib crane 10 having an upstanding column 11 formed from a cylindrical pipe, and having a mounting base 12 formed from a flat base plate 13 that is joined to the lower end faces of the column 11 by welding, and which is braced with respect to the column by means of angular gusset plates 14 that are disposed between the base plate 13 and the column 11 in plates passing through the axis of the column and located at

2

equally spaced intervals about the axis of the column. The base plate 13 is adapted to be secured to the floor or any other mounting surface by means such as anchoring bolts 15 that are passed downwardly through appropriate openings 13A formed in the base plate 13.

At its upper end, the column 11 is arranged to rotatably support a projecting jib 20 which is, in the present instance, arranged in a horizontal position. The jib 20 as herein shown is formed by an I beam that has upper 10 and lower flanges 20U and 20L, and an intermediate connecting web 20W that is located in a vertical plane. At the inner end of the jib 20, means are afforded for supporting the jib on the top of the column 11, and, as herein shown, such means comprise a pair of gusset or 15 side plates 21 that are disposed along opposite edges of the webs 20U and 20L in an opposed or symmetrical relationship, and are welded or otherwise securely fixed to these flanges 20U and 20L. The gusset or side plates 21 extend downwardly along opposite sides of the column 20 11 in a parallel relation to the axis of the column and to each other, and the lower flange of the jib 20 is disposed directly over and in parallel relation to the upper end of the column 11. The vertical forces between the jib 25 and the column are, in the present instance, arranged to be taken by means such as a ball thrust bearing 22 that may be appropriately secured in position with these parts in accordance with common practice.

The gusset or side plates 21 serve as a mounting means for bearings that absorb the other forces applied to the jib 30 20, and such bearing means, in accordance with the present invention, comprise an upper roller bearing unit 25U and a lower bearing unit 25L which are of identical position and which differ only in their specific location between the two side plates 21.

35 The bearing units 25L and 25U each comprise a rocking carrier 26 having parallel top and bottom walls 26U and 26L connected rigidly in spaced relation by end walls 26E. The end walls 26E are spaced apart in such a dimension that the carrier 26 will fit loosely between the 40 side plates 21, as shown in Fig. 3, and the carrier is mounted in this position by a mounting bolt 27 that extends through the two side plates 21 and the end walls 26E. Between the horizontal walls 26U and 26L of the carrier 26, a pair of rollers 28 are rotatably mounted 45 on vertical axes by mounting pins 29, and these rollers 28 are symmetrically located with respect to the ends of the carrier 26 so that they may bear against the column 11 in a symmetrical relation with respect to a vertical plane passing through the horizontal axis of the jib 20 50 and the vertical axis of the column 11. The edges of the horizontal walls 26U and 26L that are adjacent the rollers 28 are cut away arcuately as at 26C, Fig. 3, for clearance purposes. The rollers 28 may bear with a true rolling action by reason of the self adjusting action that is provided by the pivotal mounting of the carrier 26 on the bolt 55 27. The maximum range of automatic pivotal adjusting or conforming movement of the carriers 26 that is required is, of course, relatively small, and hence I prefer to afford limit stops 30 on the inner faces of the side plates 60 21 for engagement by the upper and lower edges of the carrier 26, as shown particularly in Figs. 3 and 4 of the drawing.

By reason of the improved bearing mounting that is thus afforded under the present invention, it has been 65 found that lack of uniformity of dimension and circularity of the columns 11 becomes an unimportant consideration in the manufacturing operations involved, and the mounting of the bearing rollers is materially simplified and rendered more economical. Moreover, the wearing 70 characteristics of the structure are so improved as to minimize wear and insure proper and effective operation of the crane.

Thus, while I have illustrated and described the preferred embodiment of my invention, it is to be understood that this is capable of variation and modification, and I therefore do not wish to be limited to the precise details set forth, but desire to avail myself of such changes and alterations as fall within the purview of the following claims.

I claim:

1. A jib crane structure comprising a vertical standard having an approximately cylindrical outer surface in the upper end portion thereof, a jib having one end overlying the top end of the standard, a thrust bearing supporting said one end of the jib on the top end of the standard, and bracing means between the jib and the standard, said bracing means comprising a pair of elongate rigid members secured to opposite sides of the jib at said one end and extending downwardly therefrom in spaced relation with the standard and having the standard positioned centrally therebetween, a pair of bearing carriers each comprising an elongate frame embodying top and bottom walls and rigid end walls, the carriers being on opposite sides of the standard and extending transversely thereof between said rigid members with said end walls each positioned adjacent to the inner side of a rigid member, one of said carriers being adjacent to the top of the standard and the other carrier being a substantial distance below the first carrier, the carriers extending in a direction perpendicular to the length of the jib, means pivotally coupling the said end walls of said carriers to the adjacent rigid members for oscillation of the carriers on axes

extending transversely of the standard and of the jib, and roller members disposed between the top and bottom walls of each of the carriers and each roller member being located adjacent to an end wall and pivot mounting pins for the roller members extending between said top and bottom walls of the carriers and rotatably maintaining the roller members in position for rolling engagement with said surface of the standard.

2. The invention according to claim 1, wherein said means pivotally coupling the said end walls of each of the carriers to the rigid members comprises a pivot pin extending through the length of the carrier between the top and bottom walls thereof and lying across and closely adjacent to the peripheries of the rollers and in a plane passing between the ends of the rollers, and said top and bottom walls of each of the carriers having edges in closely spaced relation with the adjacent standard and arcuately recessed to partially receive the standard.
